[57] CLAIM

The ornamental design for the open bag support, as shown.

DESCRIPTION

FIG. 1 is a perspective view of the open bag support showing my new design;

FIG. 2 is a front elevational view thereof, the rear elevational view being identical;

FIG. 3 is a right side elevational view thereof, the left side elevational view being identical;

FIG. 4 is a top plan view thereof; and,

FIG. 5 is a bottom plan view thereof.
